[57] CLAIM

The ornamental design for a rake-like golf ball retriever, as shown and described.

DESCRIPTION

FIG. 1 is a perspective view of the rake-like golf ball retriever showing my new design;
FIG. 2 is a front end elevational view thereof;
FIG. 3 is a rear end elevational view thereof;
FIG. 4 is a side elevational view thereof, the side opposite being a mirror image of the side shown in FIG. 4;
FIG. 5 is a top plan view thereof; and,
FIG. 6 is a bottom view thereof.

FIG. 3.
